By Banning & Banning, Attys.

UNITED STATES PATENT OFFICE.

CORA A. BUTLER, OF CHICAGO, ILLINOIS.

DESIGN FOR A CASING FOR FACE-STEAMERS.

SPECIFICATION forming part of Design No. 24,990, dated December 17, 1895.

Application filed October 11, 1895. Serial No. 565,418. Term of patent 14 years.

To all whom it may concern:

Be it known that I, CORA A. BUTLER, a citizen of the United States, residing at Chicago, Cook county, Illinois, have invented and produced a new and original Design for a Casing for Face-Steamers, reference being had to the accompanying drawing, forming a part hereof.

In the accompanying drawing the figure is an elevation of my casing for face-steamers.

10 The leading feature of my design consists in the casing for a face-steamer comprising a conical-shaped body portion having a diminished projecting, irregularly-curved stem portion with enlarged portions thereon.

15 A is a body portion of the casing, which is

conical in shape, and which is provided near the apex *a* with a diminished irregularly-curved projecting portion *B*. This diminished irregularly-curved portion *B* is provided with enlarged portions *C* near one end and *D* at the end, the conical-shaped portion *D* at the end, the whole presenting to the eye a harmonious and ornate figure, as illustrated in the drawing.

I claim—

The design for a casing for face steamers 25 herein shown and described.

CORA A. BUTLER.
